UNITED STATES PATENT OFFICE.

MAX TROYER, OF PRAGUE, AUSTRIA-HUNGARY.

CRANE-OPERATING GEARING.

No. 844,058.

Specification of Letters Patent.

Patented Feb. 12, 1907.

Application filed December 15, 1905. Serial No. 291,904.

To all whom it may concern:

Be it known that I, MAX TROYER, a subject of the Emperor of Austria, residing at Prague, Empire of Austria, have invented 5 certain new and useful Improvements in Crane-Operating Gearing; and I do hereby declare the following to be a full, clear, and exact description of the invention, such as will enable others skilled in the art to which it appertains to make and use the same.

My invention relates to cranes of that class in which a carriage adapted to run on overhead rails carries a lifting mechanism for raising and lowering the load, a motor for actuating the raising mechanism, and a running mechanism for moving the carriage along the overhead rails.

My invention consists in mounting in the carriage the motor and intermediate gearing, 15 if such be used, together with two or more gearing elements in such a manner that the motor may be coupled with the one or the other of such gearing elements or may be uncoupled from all of them.

20 One or more of the gearing elements may be connected to the hoisting mechanism and the other or others to the running mechanism, so that the motor may either operate the hoisting mechanism or cause the carriage to travel along its overhead rails.

25 In the accompanying drawing the figure is a diagrammatical side elevation of a crane-operating gearing constructed in accordance with my invention.

30 1 is a carriage, indicated in dotted outlines, and the straight full line 2 indicates the overhead rails along which this carriage is adapted to travel on wheels 3 4.

35 *a* indicates the motor-casing pivoted in the carriage 1 at *b*.

40 *c* indicates a mechanism for actuating the motor-casing, which mechanism, as shown in the drawing, consists of a screw-spindle 5, provided with a hand-wheel 6 and engaging 45 into a nut 7, fixed to the carriage 1. This screw-spindle is free to revolve in a sleeve 71, but is coupled therewith as to longitudinal movement, and the sleeve is pivotally connected to the motor-casing *a* by a link 8. In 50 the carriage there is mounted a running-gear *d*, which, as indicated in the drawing, consists of two spur-wheels, one of which, 9, is journaled in the carriage and meshes into the

other, 10, keyed to the shaft of the running-wheel 3, and besides there is mounted in the 55 carriage a hoisting mechanism, which, as shown in the drawing, consists of a pulley 11, a block 12, and a chain or rope 13.

To the running mechanism *d* there is connected a gearing element, which, as indicated 60 in the drawing, consists of a spur-wheel 14 on the axis of and secured to the spur-wheel 9, and to the hoisting mechanism there is connected another gearing element, which, as indicated in the drawing, consists of a spur- 65 wheel 15 on the axis of and secured to the pulley 11.

16 is a gearing element mounted on the motor-casing and driven by the motor and consisting, as indicated in the drawing, of a 70 pinion adapted to engage with either the spur-wheel 14 or the spur-wheel 15.

In the position of the parts shown in Fig. 1 the pinion 16 is out of engagement with both the spur-wheels 14 and 15, so that neither the 75 running mechanism nor the hoisting are operated by the motor. If it is desired to operate the hoisting mechanism, it is only necessary to turn the spindle 5 by the hand-wheel 6 until the motor-casing *a* has been turned 80 round its pivot *b* far enough to the left as to bring the pinion 16 into engagement with the spur-wheel 15. Then this latter, and with it the pulley 11, will be turned. If it is desired to operate the running mechanism, the 85 motor-casing is turned to the right by operating the spindle 5 until the pinion 16 comes into engagement with the spur-wheel 14, whereby the running-wheel 3 will be revolved and the carriage caused to travel. 90

The motor used may be of any desired construction; but I prefer to use a reversible motor.

I claim—

In combination with a crane - carriage 95 adapted to run on an overhead track and a running mechanism adapted to drive such carriage along said track, a hoisting mechanism mounted in such carriage, a plurality of gearing elements mounted in the carriage, 100 part of which are adapted to drive the running mechanism and the remainder of which to drive the hoisting mechanism, a casing pivotally mounted in the carriage, a motor and a gearing element adapted to be driven 105 thereby, such motor and gearing elements

being mounted in the said casing and means
for rocking the casing to and fro whereby the
gearing element driven by the motor may be
brought into engagement with any of the
5 gearing elements of the running mechanism
and hoisting mechanism, substantially as and
for the purpose described.

In testimony whereof I have signed my
name to this specification in the presence of
two subscribing witnesses.

MAX TROYER.
